UNITED STATES PATENT OFFICE.

GEORGE H. STOUT, OF DENVER, COLORADO, ASSIGNOR OF TWO-THIRDS
TO LUCIUS A. TURNER AND JOSEPH E. BRENDLINGER, OF DENVER,
COLORADO.

LOCK.

SPECIFICATION forming part of Letters Patent No. 740,060, dated September 29, 1903.

Application filed September 12, 1902. Serial No. 123,114. (No model.)

To all whom it may concern:

Be it known that I, GEORGE H. STOUT, a citizen of the United States of America, residing at Denver, in the county of Arapahoe and State of Colorado, have invented certain new and useful Improvements in Door-Locks; and I do declare the following to be a full, clear, and exact description of the invention, such as will enable others skilled in the art to which

it appertains to make and use the same, reference being had to the accompanying drawings, and to the figures of reference marked thereon, which form a part of this specification.

15 My invention relates to improvements in door-locks, my object being to provide a lock which shall be devoid of springs, thus doing away with a troublesome element which frequently breaks or gets out of place, rendering the lock useless until repairs are made. Springs also cause difficulty in assembling the lock mechanism. In my improved lock the bolt normally maintains the locking position by gravity. The bolt consists of a comparatively heavy plate pivoted at its lower rear corner, through which the knob-spindle passes. This plate has a projection which when in its normal position projects through the opening in the edge of the casing and enters the keeper-socket in the door-jamb. The lock consists, further, of key-operated and night-latch tumblers, all as hereinafter explained in detail.

My further object is to provide a lock of this class which shall be extremely simple in construction, economical in cost, reliable, durable, and efficient in use; and to these ends the invention consists of the features, arrangements, and combinations hereinafter described and claimed, all of which will be fully understood by reference to the accompanying drawings, in which is illustrated an embodiment thereof.

In the drawings, Figure 1 illustrates my improved lock mechanism, one side of the casing being removed, the bolt-plate and locking-tumblers being shown in two positions, one in full lines and the other in dotted lines. Fig. 2 shows the lock mechanism from the

opposite side, the lock being turned over or shown in the reversed position, showing its adaptation for use in either position without changing the relative arrangement of the parts. Figs. 3 and 4 are side and edge views, respectively, of the key-operated tumblers shown in detail. Fig. 5 is a section taken on the line 5 5, Fig. 4. In Figs. 4 and 5 the key and the rotary barrel forming the bearing for the tumbler are shown in place. Fig. 6 is a fragmentary front view of the casing, showing the key in place and in section. Fig. 7 is a detail view of the key. Figs. 8 and 9 illustrate the keeper-plate attached to the door-jamb in two positions.

The same reference characters indicate the same parts in all the views.

Let the numeral 5 designate the lock-casing, which has an opening 6 in its free edge to allow the bolt to protrude in the usual manner. The bolt-plate 7 is of sufficient thickness to fill the space between the front and rear plates of the casing, whereby the said plate is maintained in position at all times. This plate is provided at what will be termed its "lower rear corner" with bearings engaging the casing and through which an opening 8, angular in cross-section, is formed for receiving the operating knob-spindle, which is of ordinary construction. The central part of the plate 7 is provided with a slot 9, through which a post 10, fast to one side of the casing, passes. This post is internally threaded to receive a screw 12, which holds the detachable casing-plate in place. The slot 9 permits the bolt-plate to move freely without striking the said post.

The front portion 7^a of the plate 7 consists of a part adapted to protrude normally from the opening 6 in the front edge of the casing. This part 7^a is provided with an offset or shoulder 7^c, which engages the lock-casing at the lower extremity of the opening 6 when the bolt-plate is in the locking position.

The key-operated tumbler 12 is mounted on a barrel 13, whose extremities are journaled in the sides of the lock-casing. This barrel is open to receive the key 14. This opening in the barrel consists of a cylindrical

central bore for the key-stem and a slot for the key-blade 14. The key can only be inserted when the barrel is turned to register with one of the notches 12^a, formed in the 5 tumbler 12. The barrel is turned to this position by the engagement of the part 14^c of the key-blade with the slot of the barrel, and when in this position the widest part 14^d of the key-blade slips into place, and when the 10 key is turned to operate the tumbler the part 14^d of the key-blade engages a slot 12^c, formed in the tumbler, and moves in the slot without moving the tumbler until the end of the slot is reached, when the tumbler is actuated 15 sufficiently to permit the key to make an entire revolution, whereby it may be drawn through a slot 5^a, (see Fig. 6,) formed in the front plate of the casing. The slot 12^c of the tumbler may be varied at pleasure in 20 order to adapt the lock for keys whose blades vary, so that no two locks require exactly the same key. It is evident that instead of a single slot 12^c, formed in the tumbler, several slots may be formed. It is also evident 25 that this construction will permit the necessary variations for the purpose stated.

The bolt-plate 7 is provided with a notch or recess 7^d in its rear edge, into which the tumbler 12 may be turned by the key until 30 it reaches the position shown in full lines in Fig. 2 and by dotted lines in Fig. 1 or until a projection 12^d on the tumbler engages a projection 7^e on the lock-plate, which last-named projection forms a stop against further movement of the tumbler in that direction. When 35 the tumbler 12 is in this position, the bolt-plate is locked against movement. On the other hand, when the tumbler 12 is in the full-line position in Fig. 1 or the dotted-line position in Fig. 2 the bolt-plate may be operated 40 by the knob-spindle or thrown to the dotted-line position in Fig. 1.

The lock is also provided with a night-latch tumbler 15, operated from the inside by a 45 suitable spindle 16, which is fitted into a square opening in the tumbler. The bolt-plate is provided with a recess 7^h, into which the tumbler 15 may be turned, as shown by dotted lines in Figs. 1 and 2, whereby the 50 bolt-plate is locked against movement. When this tumbler is thrown to the full-line position in Figs. 1 and 2, the bolt-plate may be thrown by the knob-spindle to the dotted-line

position in Fig. 1, allowing the door to be opened.

55

The keeper-plate 17 employed in connection with my improved lock is illustrated in Figs. 8 and 9. This plate is provided with an inclined striking part 17^a, having shoulders 17^c, adapted to force the projecting part 7^a of the bolt-plate inwardly to the dotted-line position in Fig. 1 during the act of closing the door, after which the said projection 7^a will enter the opening 17^d of the keeper-plate, or, in other words, the bolt-plate will then fall 60 to the full-line position in Figs. 1 and 2 by gravity.

65

The lock mechanism may be adapted for use on doors turning in either direction by simply turning over the casing or changing 70 it from the position shown in Fig. 1 to the position shown in Fig. 2. The position of the keeper-plate is then reversed by turning it so that what was formerly its upper extremity shall be its lower extremity. This manipulation 75 of the parts is the only change required to accomplish the purpose stated.

75

Having thus described my invention, what I claim is—

In a door-lock, the combination with a suitable casing, a bolt-plate having a projection formed on its upper front edge, said plate being pivoted in the casing at its rear lower corner so as to cause the bolt to assume by gravity a position whereby the projection 85 thereon protrudes through an opening in the front of the casing, a knob-spindle passing through the casing and forming the pivot of said plate, a notch formed in the plate adjacent to the spindle, a night-latch tumbler 90 journaled in the casing to engage said notch, a second spindle suitably mounted on the inside of the door and connected in operative relation with the said tumbler, a second notch formed above the first-mentioned notch, and 95 a second tumbler and a key for operating said second tumbler to cause the same to engage said second notch to hold the bolt-plate in locked position.

95

In testimony whereof I affix my signature 100 in presence of two witnesses.

GEORGE H. STOUT.
